UNITED STATES PATENT OFFICE.

FRED T. MELLOR, OF FINLEYVILLE, PENNSYLVANIA.

RAIL-CLAMP.

1,316,173.

Specification of Letters Patent. Patented Sept. 16, 1919.

Application filed June 13, 1919. Serial No. 303,867.

To all whom it may concern:

Be it known that I, FRED T. MELLOR, a citizen of the United States, residing at Finleyville, in the county of Washington 5 and State of Pennsylvania, have invented new and useful Improvements in Rail-Clamps, of which the following is a specification.

This invention relates to a rail clamp and 10 has for its primary object to provide a device of this character of simple, substantial construction, automatic in its operation and very effective in gripping a rail and preventing creeping thereof.

15 An object of the invention is to provide a simple form of rail clamp active under all conditions to effectively grip the rail and prevent movement thereof.

Besides the above my invention is distinguished 20 in the use of two plates resiliently connected together so as to be forced at all times into proper engagement with the rail.

With these and other objects in view the 25 invention will be better understood from the following detailed description taken in connection with the accompanying drawing, wherein:

Figure 1 is a sectional view of the rail 30 showing my invention applied thereto.

Fig. 2 is a side elevation thereof.

Fig. 3 is a sectional view through one of the plates.

Fig. 4 is a side elevation of one of the 35 plates.

Again referring to the drawing illustrating one of the many forms in which the invention may be constructed, the numerals 1 and 2 designate a pair of plates of identical construction each having a recess 3 for receiving the base of the rail B and a depending lug 4 arranged to engage the side of the tie C thereby preventing the rail from creeping. For the purpose of facilitating 45 the engagement between each plate and the base, one wall of the recess 3 is serrated as indicated at 5 so as to bite into the base of the rail and this action may be quickly accomplished by striking the plate with a 50 hammer in the vicinity of the point 6. For the purpose of drawing the plates toward each other for engagement with the base, I

provide a coil spring 7 that has its end portions embedded in the plates and secured thereto as indicated at 8. By this arrangement it will be seen that the plates are continuously drawn toward each other so as to effectively engage the base of the rail and in such a manner that an effective grip is accomplished between the plates and the rail so that when the lugs 4 are arranged in engagement with the tie the rail will be effectively held against creeping. It is of course to be understood that portions of the plate may be changed so as to coöperate with or be formed into the usual fish plates that are bolted to the ends of adjacent rails.

From the foregoing description taken in connection with the accompanying drawing it should be apparent that I provide a rail clamp of simple, substantial construction that will not work loose and will effectively hold a rail against creeping. It is of course to be understood that the construction of the various parts and their associations may be changed in various manners and therefore I do not desire to be limited in any manner except as set forth in the claims hereunto appended.

Having described my invention, what I claim is:

1. A rail clamp comprising a pair of plates yieldably connected together for engagement and disengagement with the base 85 of a rail.

2. A rail clamp comprising a pair of plates constructed to engage the base of a rail and a yieldable element for drawing the plates into engagement with the base. 90

3. A rail clamp comprising a pair of plates constructed to engage the base of a rail and a yieldable element for drawing the plates into engagement with the base, each of said plates having a portion thereof serrated so as to bite into said base. 95

4. A rail clamp comprising a pair of plates constructed so that when moved toward each other the same will effectively engage the base of the rail and a contractile 100 spring having its ends connected to said plates.

In testimony whereof I affix my signature.

FRED T. MELLOR.
